DESIGN FOR A TEXTILE FABRIC

Arthur de Gerard, New York, N. Y.

Application December 8, 1938, Serial No. 81,653

Term of patent 3½ years

To all whom it may concern:

Be it known that I, Arthur de Gerard, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein the figure is a plan view of a piece of textile fabric showing my new design.

The design is characterized by a series of flowers arranged in units of four facing opposite poles, and comprises outlined petals with plain centers arranged in groups around a common center, said petals being interspersed by short dash lines in an allover direction as shown.

I claim:

The ornamental design for a textile fabric, substantially as shown and described.

ARTHUR DE GERARD.
